(57) **CLAIM**

The ornamental design for a display screen or portion thereof with graphical user interface as shown and described.

DESCRIPTION

Display screen or portion thereof with graphical user interface

1.1: Front view

The solid line rounded rectangle, along with the three circles indicated by dash-dot broken lines, depicts the display screen. The broken lines that lie outside the solid line rounded rectangle and the broken lines that lie inside the three circles indicated by dash-dot broken lines depict environment. The broken lines that lie between the inside of the solid line rounded rectangle and the outside of the three circles indicated by dash-dot broken lines illustrate portions of the graphical user interface. All the dash-dot broken lines and broken lines form no part of the claimed design.
